A. P. BROOMEELL.
AUTOMATIC HEAT REGULATOR.
APPLICATION FILED OCT. 4, 1912.

1,068,216.

Patented July 22, 1913.

UNITED STATES PATENT OFFICE.

ALBERT P. BROOMEML, OF YORK, PENNSYLVANIA.

AUTOMATIC HEAT-REGULATOR.

1,068,216.

Specification of Letters Patent.

Patented July 22, 1913.

Application filed October 4, 1912. Serial No. 723,876.

To all whom it may concern:

Be it known that I, ALBERT P. BROOMEML, a citizen of the United States, and a resident of York, in the county of York and 5 State of Pennsylvania, have made certain new and useful Improvements in Automatic Heat-Regulators, of which the following is a specification.

My invention relates to improvements in 10 automatic heat regulators, and it consists in the combinations, constructions, and arrangements herein described and claimed.

An object of my invention is to provide 15 a magnetic device which may open and control valves, such as the valves of radiators, dampers, hot air flues and the like.

A further object of my invention is to 20 provide means controlled by a thermostat for operating the valves and for effectively locking the valve in its closed position, thereby resisting pressure tending to open 25 it, but which will automatically operate to release the valve and to withdraw it from its seat when the temperature has reached 25 a certain point.

A further object of my invention is to 30 provide a simple device for accomplishing the above named objects, which is made of few parts, and which is therefore not liable 35 to easily get out of order.

Other objects and advantages will appear in the following specification, and the novel features of the device will be particularly pointed out in the appended claims.

35 My invention is illustrated in the accompanying drawings forming part of this application in which—

Figure 1 is a longitudinal section through the device, Fig. 2 is a transverse section 40 through the device, Fig. 3 is a plan view of the device, and Fig. 4 is a diagrammatic view showing the electric connections.

In carrying out my invention I make use 45 of a part of the heating apparatus, such as the valve of a radiator. Such a valve I have shown at 1 in Figs. 1 and 2. This valve is designed to engage the valve seat 3, so as to cut off or establish communication with the interior 4 of the valve casing 5 on the opposite side of the valve seat from the valve 2.

Secured to the valve casing 5 is a plate 50 or cap 6 to which is secured at its ends the yokes 7 and 8 of the cylinders 9 and 10 respectively, screws 11 being provided for that

purpose. Between the yokes 7 and 8 and the cap or plate 6 are a series of thin spacing plates 12 whose purpose will be explained later. A description of the construction of one solenoid will suffice, since they are both 60 precisely alike. The yoke 7 has secured to it by means of screws 13^a an inwardly projecting extension 13, which has a recess 13^b at one end. A cylinder 14 is supported on the extension 13, and is provided on its exterior with the insulating heads 15 and 16 respectively. Between these heads the wire of the solenoid is wound.

The yoke 7 is provided with an opening having an insulating bushing 17 therein. A 70 core 18 is provided for each solenoid, these cores being connected by means of a bar 19.

On each side of the bar 19 are the links 20 (see Fig. 2). The pivot pin, or shaft, 21 also bears rollers 22 outside of the frame 75 20. The links 20 are pivotally connected by means of the pivot pin 23 with the valve stem 24 of the valve 2. This valve stem is provided with a packing gland 25.

Secured to the yoke 8 are L-shaped members 26, which are designed to form abutment members for the rollers 22. Each yoke is provided with a pair of spring contacts such as those shown at 27 and 28 on the yoke 7 and 29 and 30 on the yoke 8. The 85 ends of these contacts are normally together, and are turned outwardly as clearly shown in the drawing.

Disposed upon the bar 19 is an upwardly projecting member 31 at the top of which is 90 an insulating bar or rod 32. Above the insulating bar 32 is a T-shaped member 33. The bar 32 is clamped between the lower and upper members 31 and 33 by means of a screw 34.

95 Secured to the yoke 7 by means of screws 35 is an end plate 36. A similar end plate 37 is secured to the yoke 8. A casing 38 is provided and extends between the heads 36 and 37. This casing is provided with a pair 100 of openings 39 and 40. The T-shaped member 33 bears on one of its laterally extending arms the word "shut" as shown at 39^a in Fig. 3, while the other arm bears the word "open" as shown at 40^a in Fig. 3.

105 In Fig. 4 I have shown the circuit connections by means of which the device is operated. These consist of a thermostat 41, battery 42, and an insulating plate 43 having binding posts 44, 45 and 46.

A description of the operation of the circuits will be best understood by a statement of the operation of the device.

The thermostat 41 may be of any approved type to operate at any predetermined temperature. In Fig. 4, I have shown the thermostat as being in engagement with the contact 47. Battery current will now flow from the battery 42 through 41, 47, 48, 44, 49, solenoid 9, 27, 28, 50, 45, 51, and back to battery. This will energize the solenoid 9 and draw the core into the position shown in Fig. 1. Just at the end of the movement of the core, the insulating bar 32 will enter between and separate the spring contacts 27 and 28, thereby cutting off the current. The valve 1 will be opened, and will stay open until the temperature increases sufficiently to move the thermostat over against the opposite contact 52. When the thermostat member 41 is in engagement with the contact 52 the current will flow from battery 42, through 41, 52, 53, 46, 54, solenoid 10, 29, 30, 50, 51 to battery. This will energize the solenoid 10 and the core will be drawn away from the solenoid 9. At the end of its movement the insulating member 32 will enter between and separate the spring contacts 29 and 30, thereby cutting off the current.

The movement of the core toward the solenoid 10 will cause the valve to engage its seat. The links 22 will then be in the dotted line position shown in Fig. 1. Pressure against the valve will tend to be resisted by the abutment member 26, and therefore the valve is positively held against pressure. When, however, the temperature has so far decreased as to cause the movement of the thermostat, the solenoid 9 will move the core as heretofore explained. This movement is facilitated by means of the rollers 22, which tend to decrease the friction so as to permit the movement of the core to open the valve. As the T-shaped member 33 is shifted, it brings the words "shut" and "open" before the respective openings 39^x and 40^x, so that the user of the device may always know the position of the valve.

It will be noted that in my device the current is cut off as soon as the solenoid has done its work. There is therefore a great economy in current, because the period between the vibration from one contact to another may represent a considerable time, and if the current were on the solenoids it would not only result in waste of current, but in an undue extension of the parts, due to the heating of the coils and would interfere with the proper operation of the device. The feature of the positive locking of the valve I regard as very important. This permits the device to be used with systems having either high or low pressure. It will be noted that the valve is moved by the sole-

noid regardless of the pressure. Thus when it is used with a system having very low pressure, the valve is positively opened, as effectively as if it were used on a system having pressure behind the valve.

In order that the valve 1 may be brought into position upon its seat, I provide the spacing plates 12 which may be made of any suitable material. These plates may be used so as to bring the valve to its proper position. As the valve becomes worn, adjustment may be necessary, and certain of these parts may be removed or replaced in order to bring the valve into its proper position for closing at the right moment.

I claim:

1. The combination with a thermostat and a source of current, of a valve operating device controlled by the thermostat, said valve operating device comprising a pair of solenoids each provided with a core, a rigid member connecting said cores, connections between the valve stem and said rigid connecting member for operating the valve, said connections comprising links pivotally secured to said rigid connecting member at one end and to the valve stem at the other, friction rollers carried by the pivotal connection of the links with the rigid member, and an abutment member arranged to be engaged by the periphery of said rollers.

2. In a heat regulating device, the combination with a valve having a valve stem, of a pair of solenoids secured to the valve casing, movable cores for said solenoids, a bar rigidly connecting said cores together, links pivotally connecting said rigid bar with said valve stem, a pair of normally closed spring contacts carried by each solenoid, an insulating plug carried by said bar and arranged to enter between and to separate either pair of said closed contacts, an interior casing provided with openings, and an indicating device carried by said insulating plug and having portions arranged to register with the openings to indicate the position of the bar.

3. In a heat regulating device, a valve casing, a pair of yokes secured to said valve casing, a pair of solenoids carried by said yokes, a core for each solenoid, a common connecting bar for said cores, a valve in said valve casing having a slideable valve stem, a pair of spring contacts carried by one of said solenoids, an insulating plug carried by said bar and arranged to enter between and to separate said pair of contacts and to be frictionally held by said contacts, and means connecting the valve stem and the common connecting bar for operating the valve through the motion of the bar.

4. In a heat regulating device, a valve casing, a pair of yokes secured to said valve casing, a pair of solenoids carried by said yokes, a core for each solenoid, a common

connecting bar for said cores, a valve in said valve casing having a slidable valve stem, a pair of spring contacts carried by one of said solenoids, an insulating plug carried by said bar and arranged to enter between and to separate said pair of contacts and to be frictionally held by said contacts, and means connecting the valve stem and the common connecting bar for operating the valve through the motion of the bar, said means comprising links secured to said valve stem at one end and to the common connecting bar at the other and arranged to be brought into alinement with the valve stem when the insulating core has entered between the spring contact members.

5. In a heat regulating device, a valve casing, a pair of yokes secured to said valve casing, a pair of solenoids carried by said yokes, a core for each solenoid, a common connecting bar for said cores, a valve in said valve casing having a sildable valve stem, a pair of spring contacts carried by one of said solenoids, an insulating plug carried by said bar and arranged to enter between and to separate said pair of contacts and to be frictionally held by said contacts, means connecting the valve stem and the common connecting bar for operating the valve through the motion of the bar, said means comprising links secured to said valve stem at one end and to the common connecting bar at the other end and arranged to be brought into alinement with the valve stem when the

insulating core has entered between the 35 spring contact members, and means for relieving the connecting rod from end thrust of the links when the latter are in alinement with the valve stem.

6. In a heat regulating device, a valve 40 casing, a pair of yokes secured to said valve casing, a pair of solenoids carried by said yokes, a core for each solenoid, a common connecting bar for said cores, a valve in said valve casing having a slidable valve 45 stem, a pair of spring contacts carried by said bar and arranged to enter between and to separate said pair of contacts and to be frictionally held by said contacts, means connecting the valve stem and the common 50 connecting bar for operating the valve through the motion of the bar, said means comprising links secured to said valve stem at one end and to the common connecting 55 bar at the other end and arranged to be brought into alinement with the valve stem when the insulating core has entered between the spring contact members, and means for relieving the connecting rod from end thrust of the links when the latter are 60 in alinement with the valve stem, said means comprising an L-shaped abutment member secured to one of said solenoids.

ALBERT P. BROOMEELL.
